(57) **CLAIM**

The ornamental design for footwear sole, as shown and described.

DESCRIPTION

FIG. 1 is a perspective view of the footwear sole embodying the new design;

FIG. 2 is a bottom view thereof;

FIG. 3 is a right side view thereof, reduced in scale;

FIG. 4 is a left side view thereof, also reduced in scale;

FIG. 5 is an enlarged front view of FIG. 1; and,

FIG. 6 is an enlarged rear view of FIG. 1.

FIGS. 1–6 show features of an article of footwear in phantom lines. These features are shown for environmental purposes and do not form any part of the claimed design. Further, the phantom lines immediately adjacent the solid-line portions of the design form the boundary of the design, with the phantom lines forming no part of the claimed design.
